His Attorney.

UNITED STATES PATENT OFFICE

2,275,926

REMOVABLE BOTTOM FURNACE

Ernest A. Smith, Schenectady, N. Y., assignor to
General Electric Company, a corporation of
New York

Application April 29, 1941, Serial No. 390,933

4 Claims. (Cl. 283—40)

My invention relates to furnaces of the elevator and removable bottom type whereby after the charge in the furnace has had its temperature raised to the desired point with the bottom of the furnace in the closed position the bottom may be quickly moved to the open position to enable the charge to be lowered into a quenching tank. It is the object of my invention to provide an improved furnace of this type having simple and effective means for quickly moving the furnace bottom from one position to the other. A further object of my invention is the provision of means for effecting a horizontal translation movement of the furnace bottom and a vertical sealing movement thereof, the two movements being produced in succession by the continued operation of a single driving member.

My invention will be better understood from the following description taken in connection with the accompanying drawing and its scope will be pointed out in the appended claims.

In the drawing Fig. 1 is an end view partly in cross section of a furnace involving my invention and Fig. 2 is a side view of the same with parts in cross section.

Referring to the drawing, 1 represents the side walls and top of the furnace, the same being supported in an elevated position by the structure 2. By way of illustration I have shown a charge within the furnace comprising a series of plates 3 which are being heat treated, the furnace being heated by any suitable and well-known means, not shown, such as resistance heaters. The plates being heat treated are shown supported by the cradle 4 which is suspended in the furnace at each end by the chains 5 extending up through the top and thence over the pulleys 6 to the winch 7. By means of the motor 8 the winch may be turned to raise and lower the cradle containing the plates in a well understood manner.

The removable furnace bottom 10 is shown by full lines in the drawing in its position closing the bottom opening of the furnace and engaging the bottom walls thereof in a manner to seal the furnace. The bottom 10 is supported by a carriage comprising the upper member 11 which is constructed to receive it and adjustably support it through the adjusting screws 12 and the lower member 13 which is provided with the wheels 14 arranged to run on the track 15 supported by the I-beam 16. To maintain the two members 11 and 13 in proper relative horizontal position they are provided with co-operating guides represented in the drawing as the guide

projections 17 on the member 11 and the co-operating arm 18 on the member 13. When the carriage is in the position represented by full lines in Fig. 1, the right-hand end of the lower member 13 is in engagement with the stop 20 on the end of the I-beam 16.

The upper and lower members 11 and 13 are connected together adjacent the four corners of the upper member by toggle joint mechanism comprising four sets of toggle joint links 21. The lower ends of the links are pivoted upon the shafts 22 of the wheels 14; the upper ends of the links are pivoted on the stub shafts 23 carried by tapering extensions of the upper member 11. The intermediate portions of the sets of toggle joint links at the same end of the furnace are connected together by the bar 24 so that those toggle joint links move in unison. Connected with opposite ends of the bar 24 is the chain 26, the connection with the right-hand end of the bar being shown through the cushioning spring 27 in order to prevent damage to the mechanism by reason of overtravel of the chain after the carriage has reached the stop 20. The operating chain 28 engages the idler sprocket 29 at one side of the furnace and the driving sprocket 28 at the other side thereof. The latter sprocket is arranged to be driven in one direction or the other by the motor 30 through the reducing worm gear 31. Arranged between the lower member 13 of the carriage and the bar 24 thereof is the tension spring 32 whose function will appear later. The lower member 13 of the carriage has an arm through which is threaded the limiting screw 33 which is arranged to engage one of the toggles to prevent it from passing over center when moved from the collapsed position to the straightened position. Preferably, this screw is so adjusted that the toggles are not permitted to quite reach a straightened position.

When it is desired to remove the furnace bottom from the position shown by full lines in the drawing to one in which the charge may be lowered into a quenching tank the motor is operated to rotate the sprocket 28 in a clockwise direction. This releases any tension that may have been maintained on the spring 27 and allows or causes the toggle joint links to move from the extended position at which the furnace bottom is held firmly against the side walls of the furnace to a collapsed position as indicated by dotted lines. As a result of this movement of the toggle joint links the spring 32 is subject to greater tension, the force of which later serves

to assist the motor to straighten the links, and the limiting collapsed position of the links is determined by the stop 34. By this collapsing movement of the links the upper member 11 of the carriage and the furnace bottom 10 move straight downward until further movement of the links is arrested by the stop 34. Continued rotation of the driving sprocket 29 in the same direction results in a horizontal movement of the entire carriage with the bottom 10 thereon until it has reached a point to the left of the furnace, as seen in Fig. 1, sufficiently far removed that it will not interfere with the lowering of the charge.

After a new charge has been raised in the furnace the driving sprocket 29 is rotated in the opposite direction. Since movement of the carriage bodily to the right offers less resistance than that offered by the raising of the upper member thereof by the toggle links the entire carriage and bottom will roll to the right until the bottom reaches a position directly beneath the furnace walls. In that position the stop 20 arrests further movement of the carriage whereupon continued rotation of the driving sprocket forces the toggle links from the collapsed position to the straightened or nearly straightened position as determined by the limiting screw 33. The movement of the upper member 11 and hence of the bottom 10 as a result of straightening the toggle links is vertical, the bottom being brought up to firm or sealing engagement with the side walls of the furnace.

It will be understood that the toggle joint mechanism, the operating chain, sprockets, etc., are duplicated at the opposite end of the furnace from that shown by Fig. 1, the two driving sprockets being preferably secured to the same shaft so as to be driven by a single motor.

What I claim as new and desire to secure by Letters Patent of the United States is:

1. The combination with a furnace having side walls and a removable bottom comprising a track extending horizontally beneath the furnace, a carriage thereon including relatively movable upper and lower members, said upper member supporting said bottom, force applying means for moving said carriage horizontally on said track, a stop for limiting said horizontal movement of the lower member of said carriage, and means responsive to a continued application of force by said means after the lower member has reached said stop for raising said upper member to bring said bottom into engagement with the side walls of the furnace.

2. The combination with a furnace having side walls and a removable bottom comprising a

track extending horizontally beneath the furnace, a carriage thereon including relatively movable upper and lower members, said upper member supporting said bottom, toggle joint mechanism connecting said members, force applying means connected with a part of said toggle joint mechanism and operative through said mechanism to move the carriage on the track with the upper member thereof lowered, and a stop arranged to engage said lower member for limiting the movement of the carriage in one direction to a position in which said bottom is in a predetermined position beneath the furnace, said mechanism being responsive to the continued application of force by said means to raise said upper member thereby to bring said bottom into engagement with said side walls.

3. The combination with a furnace having side walls and a removable bottom comprising a track extending horizontally beneath the furnace, a carriage including a lower member mounted to roll on said track and an upper member arranged to support said bottom, cooperating vertical guide means on said members, toggle joint mechanism having opposite ends connected with said members, means for applying force to the intermediate portion of said mechanism when the mechanism is relatively collapsed for moving the carriage on the track from a position laterally displaced from the furnace to one beneath the same, and a stop for limiting the movement of the lower member of the carriage, the continued application of said force after the carriage has reached said stop causing said mechanism to straighten thereby causing said bottom to engage the side walls of the furnace.

4. The combination with a furnace having side walls and a removable bottom comprising a track extending horizontally beneath the furnace, a carriage including a lower member mounted to roll on said track and an upper member arranged to support said bottom, cooperating vertical guide means on said members, toggle joint mechanism having opposite ends connected with said members and constructed to raise said upper member from a lowered position when the mechanism is moved from a partly collapsed position to a straightened position, a spring tending to move said mechanism from said former position to said latter position, a motor driven chain connected with the intermediate part of said mechanism and a stop for limiting the movement of the lower member of said carriage in one direction on said track to a position in which said bottom is directly beneath said furnace.

ERNEST A. SMITH.
